CLAIM

The ornamental design for medical tubing for use with an endoscope as shown and described.

DESCRIPTION

FIG. 1 is a front elevational view of a first embodiment of a medical tubing for use with an endoscope.

FIG. 2 is a top plan view of the medical tubing for use with an endoscope of FIG. 1.

FIG. 3 is a bottom view of the medical tubing for use with an endoscope of FIGS. 1 and 2.

FIG. 4 is a left side elevational view of the medical tubing for use with an endoscope of FIGS. 1-3.

FIG. 5 is a right side elevational view of the medical tubing for use with an endoscope of FIGS. 1-4.

(Continued)

FIG. 6 is a rear elevational view of the medical tubing for use with an endoscope of FIGS. 1-5.

FIG. 7 is perspective view of the medical tubing for use with an endoscope of FIGS. 1-6.

FIG. 8 is front elevational view of a second embodiment of a medical tubing for use with an endoscope.

FIG. 9 is a top plan view of the medical tubing for use with an endoscope of FIG. 8.

FIG. 10 is a bottom view of the medical tubing for use with an endoscope of FIGS. 8 and 9.

FIG. 11 is a left side elevational view of the medical tubing for use with an endoscope of FIGS. 8-10.

FIG. 12 is a right side elevational view of the medical tubing for use with an endoscope of FIGS. 8-11.

FIG. 13 is a rear elevational view of the medical tubing for use with an endoscope of FIGS. 8-12.

FIG. 14 is perspective view of the medical tubing for use with an endoscope of FIGS. 8-13.

FIG. 15 is an enlarged view of the portion within the box identified with the number 15 on the medical tubing for use with an endoscope of FIG. 1; and,

FIG. 16 is an enlarged view of the portion within the box identified with the number 16 on the medical tubing for use with an endoscope of FIG. 8.

The break lines indicate that the appearance of any portion of medical tubing for use with an endoscope between the break lines forms no part of the claimed design.
